UNITED STATES PATENT OFFICE.

MAX COLTON, OF SAN FRANCISCO, CALIFORNIA.

DESIGN FOR A GEM FOR RINGS AND SIMILAR ARTICLES.

Application filed July 27, 1925. Serial No. 14,237. Term of patent 3½ years.

To all whom it may concern:

Be it known that I, MAX COLTON, a citizen of the Republic of Poland, residing at San Francisco, in the county of San Francisco and State of California, have invented a new, original, and ornamental Design for Gems for Rings and Similar Articles, of which the following is a specification, reference being had to the accompanying drawing, forming part thereof.

Figure 1 is a top view of a gem showing

my new design. The gem is shown mounted upon a ring, the latter being shown in dotted lines.

Figure 2 is a side view of the gem embodied in a ring indicated in dotted lines.

I claim:

The ornamental design for a gem for rings and similar articles, as shown.

In testimony whereof I affix my signature.

MAX COLTON.
